UNITED STATES PATENT OFFICE.

PAUL BAHR, OF CHICAGO, ILLINOIS.

CASKET.

1,220,487.

Specification of Letters Patent. Patented Mar. 27, 1917.

Application filed October 12, 1916. Serial No. 125,143.

To all whom it may concern:

Be it known that I, PAUL BAHR, a citizen of the United States, residing at Chicago, in the county of Cook and State of Illinois, 5 have invented certain new and useful Improvements in Caskets, of which the following is a specification.

The essential object of this invention is to provide means for hermetically sealing 10 caskets or coffins and is particularly intended to be employed in connection with those caskets which are provided with a sheathing or lining of metal or which are constructed entirely of metal.

15 In the drawings, Figure 1 is a top plan view of a casket embodying the invention; Fig. 2 is a transverse sectional view thereof; Fig. 3 is a perspective view of one of the members by which the sealing is accomplished; and Fig. 4 is a perspective view of the member which coöperates with the board shown in Fig. 3.

The casket proper 1 within which the remains to be interred are placed, may be 20 made of metal or wood sheathed or lined with metal, and at the top of the casket, the grooved receptacles 2 and 3 are placed. Said members 2 and 3 are disposed parallel to each other and one of them is fixed on 25 each side of the casket 1, being fastened to the top of the casket in any suitable manner. Inside of the members 2 and 3, the downwardly-depending tongues 4 and 5 are placed, and the overturned flanged lips 6 30 and 7 are adapted to receive and retain strips of rubber or other resilient packing 35 8 and 9.

The cover 10 of the casket is formed in the usual manner, but in addition receives the 40 tank 11, within which a quantity of water can be placed. Depending from the tank 11 is a pipe 12 controlled by valve 13 operated from handle 14 which projects outside of the 45 cover 10. Depending from the cover are the V-shaped flanged members 15 provided with a series of perforations 16, which V-shaped members 15 should preferably be of substantially the same length as the chambers 2 and 3 within which they are 50 adapted respectively to be received. The pipe 12, or at any event its discharge end, is in vertical registration with one of the V-shaped members 15.

The V-shaped members 15 may be extended 55 as a continuous flanged member on all four sides or they may be cross-connected

in any other manner so as to permit the water which drops from the pipe 12 to circulate around and fill up the space within the two arms of the V as well as to pass 60 through the perforation 16.

Within the chambers 2 and 3 a suitable quantity of cement is placed. When the casket is to be permanently closed and sealed, the cover 10 is placed in position and 65 the V-shaped flange or flanges 15 will be received within the tubular chambers 2 and 3 by retaining the cover 10 immovably in place.

In the manufacture of the caskets, the 70 cement can be placed in the chamber 2 at the factory where the goods are made up and the caskets shipped out with the cement already in place. The resilient members 8 or 9 will engage the V-shaped flanges 15, as 75 best shown in Fig. 2, and will retain the particles of cement, even when in the dry or powdered form, in place, and, when the cover 10 is lifted off, the resilient members 8 or 9 will brush or spray the sides of the 80 V-shaped flanges 15, and will remove any particles of cement which may have adhered to the flanges.

While I have illustrated and described a preferred form of construction for carrying 85 my invention into effect, the same is capable of a wide range of variation, alteration, modification and change without departing from the spirit of the invention. I, therefore, do not wish to be limited to the construction herein shown and described, but 90 desire to avail myself of all such variations, alterations, modifications and changes as fairly fall within the scope of the appended claims or may be construed to come within 95 the same by involving the doctrine of equivalents.

I claim as my invention:

1. A casket provided with a chambered receptacle adapted to hold a quantity of 100 cement, a cover provided with a flanged member adapted to project into said chambered receptacle and into the cement contained therewithin, a tank upon the cover, a pipe leading from said tank to a point 105 above the chambered receptacle, and means for controlling the flow of water from said pipe.

2. A casket provided with a chambered receptacle adapted to hold a quantity of 110 cement, a cover provided with a V-shaped flanged member adapted to project into said

chambered receptacle and into the cement contained therewithin, said V-shaped member being provided with a row of perforations adjacent the crotch of the V, a tank upon the cover, a pipe leading from said tank to a point above the chambered receptacle, and means for controlling the flow of water from said pipe.

3. A casket provided with a chambered receptacle adapted to hold a quantity of cement, a cover provided with a V-shaped flanged member adapted to project into said chambered receptacle and into the cement

contained therewithin, said V-shaped member being provided with a row of perforations adjacent the crotch of the V, a tank upon the cover, a pipe leading from said tank to a point above the chambered receptacle, and means for controlling the flow of water from said pipe, there being a pair of 15 downwardly-depending lips within said chambered receptacle, said V-shaped flanged member being received within the space intermediate said downwardly depending lips.

In testimony whereof I affix my signature.
PAUL BAHR.
